Attorney

UNITED STATES PATENT OFFICE.

WILLIAM C. KLAUSER, OF HARTFORD, CONNECTICUT.

SHIPPING RECEPTACLE.

Application filed October 2, 1920. Serial No. 414,255.

To all whom it may concern:

Be it known that I, WILLIAM C. KLAUSER, a citizen of the United States, and a resident of Hartford, in the county of Hartford and State of Connecticut, have invented new and Improved Shipping Receptacles, of which the following is a specification.

My invention relates more especially to the class of devices used for the purpose 10 of inclosing various articles of merchandise for storing and shipping purposes, and an object of my invention, among others, is to so construct such receptacles that they may be used and reused indefinitely; another 15 object of my invention is to provide such receptacles with means to enable them to be readily knocked down and again set up; and another object of my invention is to provide an extremely strong receptacle of 20 the kind herein mentioned.

One form of receptacle embodying my invention and in the construction and use of which the objects herein set out, as well as others, may be attained, is illustrated in 25 the accompanying drawings, in which—

Figure 1 is a top view of a barrel embodying my invention.

Figure 2 is a view in side elevation of 30 the upper part of the same.

Figure 3 is a view, scale enlarged, of a fragment of the barrel above mentioned, and illustrating in detail the means for securing the heads of the barrel in place.

Figure 4 is a detail view, scale enlarged, 35 illustrating the means for securing the hoops in place.

Figure 5 is a detail view in section through the fastening means for the meeting ends of the hoops.

My invention is not limited in its uses to a receptacle of any special type, but as it finds ready use in connection with receptacles of barrel-shape I have selected such 40 for the purpose of illustration and description of my invention herein. My improved package is constructed in sections of any desired number, the special package illustrated and described herein comprising two sections or barrel-halves 5 separated on a plane passing preferably through diametrically opposite sides of the structure. These sections are composed of staves 6 made preferably from wood of any suitable

width and thickness, with their edges nicely fitting one another, although I contemplate 55 iron as a very suitable material from which to construct such staves. The meeting edges of the sections may be formed in any suitable manner, as shown herein such edges being plain and abutting squarely one 60 against the other.

Said barrel sections are secured together by end hoops 7 and intermediate hoops 8 to which the staves are preferably riveted and which hoops are provided with flanges 9 of a depth sufficient to protect fastening devices for the ends of the hoops to be hereinafter described, such flanges projecting 65 farther from the outer surface of the barrel than do said fastening devices, and the 70 flanges on the intermediate hoops located nearest to the lengthwise center of the barrel serve the additional purpose of providing at least two supports separated to a considerable distance to enable the barrel 75 to be rolled without easily tipping. The ends of the staves are preferably tapered or bevelled in the usual manner to form chimes 10, and the end hoops 7 are each of trough-shape with a groove 11 extending 80 from end to end of the hoop. The outer walls 12 of the grooves in these end hoops are preferably longer than the inner walls 13 and they may terminate in beads 14. A flange 15 projects from the inner wall of 85 each end hoop, its edge being preferably overturned, as shown in Fig. 3 of the drawings, and the heads 16 of the barrel rest upon and are secured to these flanges in the following manner:

The diameters of the heads are preferably a little less than the inner diameters of the chimes, these heads being composed of any suitable material, as iron formed in a single piece, as shown in Figures 1 and 3 95 of the drawings. A band ring 17, of metal, is secured in any suitable manner at the edge of each head, and latches 18 are removably secured to these rings, as by means of screws 19, that are loosely secured to the latches as by means of collars 20 that 100 permanently secure or attach the screws to the latches. The latches are pivotally mounted on grooved clips 21, the grooves 105 in which are formed to fit over the end hoops 7, as clearly shown in Figure 3 of the

drawings. These clips are rigidly secured to the hoops, as by means of rivets passed through the clips, hoops and barrel chimes.

The end hoops, as well as the intermediate 5 hoops, are secured together, as to the ends of each hoop, by means of interengaging threaded studs and sleeves. Each hoop is provided near its opposite ends with ears 22-23 and a threaded stud 24 is secured 10 in any suitable manner to each of the ears 22, and an anchoring stud 25 is secured as may be desired to each of the ears 23. A fastening sleeve 26 is mounted on a squared part 27 of each anchoring stud, said sleeves 15 having threaded openings to receive and engage with the threads on the studs 24 as a means for drawing the ends of the hoops toward each other to bind said hoops tightly and thus securely hold the barrel sections 20 together.

It will be noted that my improved barrel is of an extremely strong construction and amply sufficient to successfully withstand the rough usage common to the handling of freight. While the construction of the package is such as to involve considerable initial expense, yet the features of strength enabling the package to be used time and time again reduces the eventual 30 expense of each package, when compared with the present method of using a package only once, to a point below the zero mark.

It will be further noted that this round 35 structure is such that when "knocked down" or disassembled, the parts may be compactly arranged by nesting one within another and thereby economizing in shipping and storage space. This provides a structure in 40 which, aside from the body and the heads, there are no detached parts, all of the fastening devices being integral with one or the other of these members. The hoops are riveted to the staves and the fastening members are all riveted or secured to their respective parts so that nothing but a wrench or a screw-driver is required to take the package down or set it up. All of the parts 45 are, therefore, intact and there is no danger 50 of loss of any of such parts.

I claim:—

1. A shipping package comprising a plurality of sections, each formed in cross section substantially on the arc of a circle, 55 bands encircling said sections at a distance from the lengthwise center thereof, flanges extending peripherally around and from said bands to provide a rolling rest for said package and a protection for means for 60 securing the ends of the band, and means for securing the ends of the band together.

2. A shipping package comprising a plurality of sections, a band extending around said sections to secure them together, ears 65 projecting from said band, studs extending

through said ears, and a fastening sleeve having an unthreaded end loosely engaging an unthreaded part of one of said studs and having a screw threaded opening to engage the screw threaded end of the other of said 70 studs to draw the ends of the band together.

3. A shipping package comprising a body part with an open end, a flange extending inwardly near the mouth of said opening, a head resting upon said flange, latches pivotally secured to the body part, and means for removably securing the latches to said head 75 to hold it in place.

4. A shipping package comprising a body part with an open end, a grooved band fitting over the edge of said open end, a flange extending inwardly within said open end, a head resting upon said flange, latches pivotally supported by said band, and means for 80 removably securing said latches to said head. 85

5. A shipping package comprising a body part with an open end, latches pivotally secured at the edge of said open end, a head for said open end, a rest for said head, and means for removably securing said latches 90 to said head.

6. A shipping package comprising a body part with an open end, latches pivotally secured at the edge of said open end, a head for said open end, a rest for said head, a band secured to the outer face of said head, and means for removably securing said latches to said band. 95

7. A shipping package comprising a body part with an open end, a grooved band fitting over the edge of said open end, grooved clips fitting over the edge of said band and secured thereto, latches pivotally supported on said clips, a head, means for supporting said head, and means for removably securing said latches to said head. 100 105

8. A shipping package comprising a body part with an open end, grooved clips fitting over the edge of the open end of said package, latches pivotally supported on said clips, a head, means for supporting said head, and means for removably securing said latches to said head. 110

9. A shipping package comprising a plurality of sections, a band extending around said sections to secure them together, ears projecting from said band, studs projecting through said ears, a fastening sleeve having an unthreaded opening engaging the unthreaded end of one of said studs, to permit movement of the sleeve toward and from the opposite stud to engage the screw threaded end thereof to draw the ends of the band together. 115 120

10. A shipping package comprising a plurality of sections forming, when placed together, a round structure with an open end and gradually increasing in diameter from each end to the lengthwise center thereof, and bands extending around said sections on 125 130

opposite sides of said lengthwise center, said bands having flanges of a width to support the package upon its side.

11. A shipping package comprising a plurality of sections forming when placed together, a round structure with an open end and gradually increasing in diameter from each end to the lengthwise center thereof,

bands with separated ends extending around the structure on opposite sides of said center, flanges extending from said bands peripherally thereof, and means for securing the ends of the bands together and projecting therefrom a distance less than the width of said flanges. ¹⁰

WILLIAM C. KLAUSER.
